REYNOLDS GUYER, OF ST. PAUL, MINNESOTA, ASSIGNOR TO WALDORF PAPER PRODUCTS COMPANY, OF ST. PAUL, MINNESOTA, A CORPORATION OF MINNESOTA

DISPLAY CARTON

Application filed September 20, 1928. Serial No. 307,270.

My invention relates to cartons and has for its object to provide a carton which may be supported in inclined position so as to readily display the goods contained within the same.

5 Another object of the invention resides in providing a carton having a closure formed with a display, said closure being adapted to be supported in a rigid and erect manner to effectively exhibit the display matter contained thereon.

Another object of the invention consists in constructing the carton with a bottom having two sides and an end connected therewith, the two sides having end sections connected there-

15 to, and in constructing said end and end sections with tongues, said carton being adapted to be folded to bring said end sections into a common plane and said tongues into the planes of said sides.

20 A still further object of the invention resides in forming said sides with flaps adapted to envelope said tongues so as to hold the carton in erected form.

A feature of the invention consists in turning back the marginal portions of said flaps so as to cause the same to overlie the bottom of the carton and in forming the bottom of the carton with abutments adapted to engage the marginal portions of the flaps to hold the same 30 in enveloping position about said tongues.

Another feature of the invention resides in spacing the ends of said flaps from said end sections to form guideways and in slidably mounting within said guideways a back 35 adapted to be raised and lowered therein.

A still further object of the invention resides in forming said back with a base portion adapted to be projected below the bottom of the carton to support the same in inclined position.

40 A feature of the invention resides in providing a closure for said carton and in folding said closure transversely so as to form a display support and a display thereon, said display being adapted to extend angularly from

said support when in erect position so as to exhibit the display matter thereon.

An object of the invention resides in connecting to said back said closure for the carton, said closure being adapted to extend into 50 said guideways upon the projection of said back below the bottom of the carton so as to hold the display support in erect position relative to the carton.

Another feature of the invention resides in forming said closure with a tongue, said tongue serving as an attaching member for supporting said display in proper position relative to said display support.

Another object of the invention resides in 60 forming the bottom, base, back and closure of said carton continuous, and in severing a portion of the bottom adjacent said base to permit of the simultaneous projection of said base below the bottom of the box and the insertion of said closure within said guides.

An object of the invention resides in forming said back with flanges adapted to be mounted for movement between said flaps and tongues so as to readily hold said back in proper position and so as to serve as stops for limiting the movement thereof.

Another feature of the invention resides in forming the display portion of said closure with side tongues for assisting in closing the box, said tongues serving as extensions for the display surface when the display is in erected position.

Other objects of the invention reside in the details of construction and in novel combination of parts hereinafter described and illustrated.

In the drawings,

Fig. 1 is a perspective view of a carton illustrating an embodiment of my invention showing the same in display position.

Fig. 2 is an end elevational view of the structure shown in Fig. 1.

Fig. 3 is a longitudinal sectional elevational view of the structure shown in Fig. 2 taken

through the center of the carton and drawn to a somewhat larger scale than Fig. 2.

Fig. 4 is a view similar to Fig. 3 showing the carton in closed position.

Fig. 5 is a plan view of the box shown in Fig. 4 in closed position, drawn to the same scale as Fig. 2.

Fig. 6 is a developed view of the formed blank from which my improved carton is constructed.

My invention comprises a box-like structure A which is formed from cardboard or similar material adapted to be scored and bent up to provide the necessary walls thereof and which is constructed open at the top. The manner of constructing the carton can best be seen in Fig. 6 which illustrates the blank from which the same is constructed. The carton blank is cut to form a bottom 10, sides 14 and 15 and an end 16. The sides 14 and 15 and end 16 are folded upwardly from the bottom 10 along score marks 11, 12 and 13, as shown in Figs. 1, 3 and 4, leaving the top of the box open. To form the end of the box opposite the end 16, the sides 14 and 15 are provided with end sections 19 and 20 which are continuous therewith and which are scored along lines 17 and 18 to permit of the folding of said end sections at right angles to said sides. When the sides 14 and 15 are bent up and the end sections 19 and 20 folded along score marks 17 and 18, said end sections lie in a common plane and form an end wall structure for the carton, which is detached therefrom at the top and bottom and which I have designated in its entirety at 41.

For holding the sides and ends of the box in erect position the end 16 is formed with two tongues 21 and 22, while the end sections 19 and 20 are similarly formed with tongues 23 and 24. These tongues are adapted to be folded away from said end and end sections along lines 25, 26, 27 and 28 so that when the entire box is folded in the proper manner, the various tongues overlie the sides 14 and 15 and are disposed in the plane thereof. Issuing outwardly from two of the edges of the sides 14 and 15 are flaps 29 and 30 which are foldable inwardly into the interior of the carton along score marks 31 and 32 parallel with the score marks 11 and 12 and spaced therefrom a distance equal to the height of the ends 16 and the end sections 19 and 20. When so disposed, the said flaps envelope tongues 21, 22, 23 and 24 and hold the bottom, sides and ends of the carton attached to one another.

For the purpose of holding the flaps 29 and 30 in proper relation, the extreme marginal portions 33 and 34 thereof are bent away from said flaps along lines 35 and 36 to overlie the bottom 10 of the carton. Along the bottom 10 are struck out abutments 37 which may be raised above the bottom proper to receive the extreme edges 70 of said marginal

portions 33 and 34, as shown in Fig. 5, which, when lodged therebetween, prevent the inward movement of flaps 29 and 30 and maintain the parts of the carton properly attached.

To prevent either of the tongues 23 or 24 from drawing out of the pockets formed between the sides 14 and 15 and the respective flaps 29 and 30, the end sections 19 and 20 are constructed with cooperating slots 38 and 39, whereby the said end sections may be interlocked to deprive the same of relative movement out of the common plane thereof. In this manner the end structure is rigidly and firmly secured together so that when the carton has been erected there is no danger of the various parts of the same becoming detached or collapsed.

The portion of the blank between the end sections 19 and 20 and tongues 23 and 24 provides a back 40 adapted to be disposed within the interior of the box and along the inner surface of the end structure 41. This portion of the blank further provides a closure 42 adapted to close the upper open end of the carton. Two score marks 43 and 44 along this portion of the blank permit of the folding of the said back and closure so as to bring the parts into proper relation with one another when the carton is closed as best shown in Fig. 4.

The back 40 in addition to supporting the closure 42 is constructed to provide an auxiliary support for the rear end of the carton which may be projected below the bottom of the carton so as to support the same in inclined position. This is accomplished as follows: A short portion of the bottom 10 of the carton indicated at 45 and disposed at the end of said bottom adjacent the back 40, is severed from the sides 14 and 15 along lines 46 and 47. This portion of the bottom is further adapted to be bent downwardly and out of the plane thereof along a transverse line 48 extending across said bottom at the ends of the cuts 46 and 47. A score mark 49 crossing the back 40, slightly above the score mark 43, permits the said back to fold along both of said score marks to form a base 50, which extends outwardly beyond the bottom of the box, as best shown in Fig. 1 when the back 40 is moved downwardly into its lowermost position. When so disposed the said base serves to support the carton in an inclined position with the rear end thereof raised somewhat above the lowermost portion of said carton.

To permit of the movement of the back 40, said back is slidably mounted between the end structure 41 and the extreme edges 51 and 52 of flaps 29 and 30, which are spaced from the said end structure, to form guideways which I have designated at 71 and 72. In addition, the back 40 is formed with two flanges 43 and 54 struck out of the material of the end sections 19 and 20, which flanges are

adapted to be bent into the planes of the sides 14 and 15 and to be lodged between said sides and the flaps 29 and 30 so as to further guide the movement of said back in its up and down movement. These flanges in addition serve 5 as stops for limiting the upward movement of the back when the portion 45 of the bottom lies in the plane of the major portion thereof and further serve as reinforcements 10 for stiffening the downwardly protruding portion of said back and supporting the base 50.

When the back 40 is moved downwardly, as shown in Fig. 3, the closure 42 which is 15 hinged thereto along the line 44, may be made to follow along the guideways 71 and 72 formed by the edges of the flaps 29 and 30 and the end structure 41. When disposed within said guideways the said closure is 20 caused to be rigidly supported in erect position extending upwardly from the carton proper in a manner to present the display matter arranged thereon.

The closure 42, in addition to closing the 25 opening in the upper portion of the carton, provides a display which is readily observable. This display is formed by folding the closure 42 transversely along a line 55 which divides the same into what I term a display support 56, being the portion of the closure supported in erect position by the guides 71 and 72 previously referred to, and a display member 57 adapted to be bent away from the plane of said support in an inclined manner, as clearly shown in Figs. 1 and 3. For assisting in holding the closure 42 in closed position, the portion of the same represented by the display member 57, is formed with three tongues 58, 59 and 60, which may be 30 folded along score marks 61, 62 and 63 along the edges of said display member. The tongue 59 is of such dimensions that the same may be bent back from the display member 57, said tongue engages the display support 56 shortly above the end structure 41 of the 35 carton. A projection 64 on the edge of this tongue is adapted to engage within a slot 65 formed in said display support, whereby the entire display structure may be rigidly held together. The tongues 58 and 60, when the 40 display is in erected position, extend outwardly therefrom in a free manner and serve to increase the area of the display member, whereby additional display matter may be 45 included, if desired. The area of the display member 57 may be further increased by cutting out a portion of the display support 56 as indicated at 67 and in terminating the 50 score mark 55 at the ends of this cut away portion so that when the said display member 57 is bent along the line 55, the said portion 67 follows with it and remains in the 55 plane thereof.

The method of erecting the carton is as follows: The back 40 and closure 42 are first

folded along the line 43 to overlie the bottom. The sides 14 and 15 are next bent up along the lines 11 and 12 and the end sections 19 and 20 brought into a common plane. As the same are brought together the said 70 end sections are interlocked along the slots 38 and 39 to form the end structure 41 and to bring the tongues 23 and 24 inwardly within the box and along the sides 14 and 15. The back 40 is now moved upwardly 75 to lie along the end structure 41 so as to bring the closure out of the interior of the box. The tongues 22 and 21 are next bent up along the lines 25 and 26 and the entire end 80 16 folded up along the line 13 to bring the said tongues in the plane of the tongues 23 and 24 and along the sides 14 and 15. Flaps 29 and 30 are next folded inwardly into the box to envelope the tongues 21, 22, 23 and 24, as well as the flanges 53 and 54 of the 85 back 40, which is held in vertical position between the edges of said flaps and the end wall structure. By inserting the edges 70 of the marginal portions 33 and 34 of the flaps 29 and 30 between the various abutments 37 90 and bottom 10, the entire structure is firmly held in erected position. The closure 42 may now be swung along the line 44 to bring the same into closing position, the tongues 58, 59 and 60 being bent at right angles to said 95 closure and being inserted within the carton between the walls thereof and the goods packed within the carton, and when so disposed the carton is completely closed and the 100 contents thereof sealed.

When it is desired to extend the carton into display position the closure 42 is opened and swung into the plane of the back 40. The entire back structure including closure 42 is then slid downwardly along the guideways 71 105 and 72 within the end of the carton, causing the base 50 to project downwardly below the bottom of the carton. As the back 40 moves downwardly the base 50 moves from the plane of said back and into a plane at right angles thereto, which causes the portion 45 of the bottom 10 to swing about the line 49 and take the position shown in Figs. 1 and 3. As the back moves downwardly the display support 56 of closure 42 follows along the said 110 guideways and becomes supported therein to hold the display in erect position. After these parts have been properly arranged the display proper 57 may be folded along the line 55 and the projection 64 inserted within the slot 65. This brings the display surface of the display 57 in a position whereby the display matter thereon may be readily exhibited. When it is desired to close the carton, the 115 reverse procedure may be followed.

My invention is advantageous in that a simple and effective device is provided, whereby goods packed within cartons may be readily displayed for sale or distribution from the same cartons in which the goods are packed. 120 130

The carton may be so disposed upon the counter of the merchant so as to be readily viewed and so as to exhibit both the display matter and the goods in an attractive and pleasing manner. The carton may be 5 constructed of a single blank cut and scored in the desired manner and may be erected quickly without the use of adhesives so that the same may be shipped in flat form, thereby 10 limiting the space utilized before erection.

Changes in the specific form of my invention, as herein disclosed, may be made with 15 in the scope of what is claimed without departing from the spirit of my invention.

Having described my invention, what I 20 claim as new and desire to protect by Letters Patent is:

1. A carton comprising a bottom, sides 25 connected to said bottom, an end connected to said bottom, tongues issuing outwardly from said end, end sections extending outwardly from the ends of said sides opposite from said end, tongues on said end sections forming a continuation thereof, said carton 30 being adapted to be folded to bring said end sections into a common plane and said tongues into the plane of said sides, flaps formed on said sides for enveloping said tongues to hold the carton in assembled position, and means for holding said flaps in the plane of said sides.

2. A carton comprising a bottom, sides 35 connected to said bottom, an end connected to said bottom, tongues issuing outwardly from said end, end sections extending outwardly from the ends of said sides opposite from said end, tongues on said end sections forming a continuation thereof, said carton 40 being adapted to be folded to bring said end sections into a common plane and said tongues into the plane of said sides, flaps formed on said sides for enveloping said tongues to hold the carton in assembled position, said flaps having the extreme edges thereof turned back to overlie the bottom of 45 the carton, and means formed on the bottom of the carton for engagement with said turned over flap portions to hold the flaps in the planes of said sides.

3. A carton comprising a bottom, sides 50 connected to said bottom, end sections issuing outwardly from the ends of said sides, tongues formed on said end sections, said tongues being a continuation thereof, said 55 carton being foldable to bring said end sections in overlying position and said tongues in the plane of said sides, flaps formed on said sides adapted to envelope said tongues and to hold the carton in erected position, 60 and means for holding said flaps in position.

4. A carton comprising a bottom, sides 65 connected to said bottom, end sections issuing outwardly from the ends of said sides, tongues formed on said end sections, said 70 tongues being a continuation thereof, said

carton being foldable to bring said end sections in overlying position and said tongues in the plane of said sides, flaps formed on said sides adapted to envelope said tongues and to hold the carton in erected position, 75 said flaps having the extreme edges thereof turned back to overlie the bottom of the carton, and abutments formed on said bottom and adapted to engage said flap portions to hold the flaps in the plane of said sides.

5. A carton comprising a bottom, sides 80 connected to said bottom, end sections issuing outwardly from the ends of said sides, tongues formed on said end sections, said tongues being a continuation thereof, said carton being foldable to bring said end sections in overlying position and said tongues in the plane of said sides, flaps formed on said sides adapted to envelope said tongues and to hold the carton in erected position, 85 means for holding said flaps in position, and a display member adapted to be inserted between the edges of said flaps and said end wall sections and to be supported in display position thereby.

6. A carton comprising a bottom, sides 90 connected to said bottom, end sections issuing outwardly from the ends of said sides, tongues formed on said end sections, said tongues being a continuation thereof, said 95 carton being foldable to bring said end sections in overlying position and said tongues in the plane of said sides, flaps formed on said sides adapted to envelope said tongues and to hold the carton in erected position, 100 means for holding said flap in position, the ends of said flaps being spaced from said end sections, a back slidable between said flaps and end wall sections, and flanges formed on said back adapted to extend between said flaps and tongues for guiding said back for sliding movement along said end sections.

7. A carton comprising a box-like structure open at the top, a closure for the opening 110 in said carton connected thereto at the rear thereof, means for supporting said closure in erect position, said closure being foldable along a transverse line to form a display support and a display member, said display member being adapted to extend in inclined position therefrom, a tongue formed on said closure adapted to hold the same in closing position relative to said carton, said tongue serving as an attaching member for holding the display member in fixed position relative to said display support, and additional tongues issuing outwardly from the display portion of said closure to further aid in effecting the closure of said carton, said second named tongues forming a continuation 120 of said display member when in erected position.

8. A carton comprising a box-like structure open at the top and having a guideway 130

along one of the walls thereof, a member connected to said box-like structure and movable along said guideway, a closure for said box-like structure, and a hinge for connecting said closure to said member, said member and closure being jointly movable along said guideway to bring said hinge to a position intermediate the ends of said guideway for restraining said closure from movement about said hinge, said closure being free at one end and foldable to provide a display, and means at the free end of said closure engaging said closure intermediate its ends for holding said display in display position.

5 about said hinge.

10 9. A carton comprising a box-like structure, having a guideway along one of the walls thereof, a member movable along said guideway and adapted to project below the bottom 15 of the carton to form a support for one end thereof, a portion of said member extending outwardly therefrom and lying along the surface on which the carton is disposed to provide a base for said member, and means 20 issuing from said base and connected to said box-like structure for bracing said member.

10 10. A carton comprising a box-like structure having a guideway along one of the walls thereof, a member movable along said guideway and adapted to project below the bottom 25 of the carton to form a support for one end thereof, a portion of said member extending outwardly therefrom and lying along the surface on which the carton is disposed to provide a base for said member, means issuing 30 from said base and connected to said box-like structure for bracing said member, and a flange issuing outwardly from said member and engaging said base for assisting in holding 35 said member in supporting position.

11. A carton comprising a box-like structure open at the top and having a guideway along one of the walls thereof, a member movable within said guideway along one of the 40 walls of said box-like structure and adapted to project below the bottom of the carton to form a support for one end thereof and a flange issuing outwardly from said member to assist in holding said member in supporting 45 position, said flange being held in outward position through engagement with another of the walls of said box-like structure.

12. A carton comprising a box-like structure open at the top, a closure therefor connected at one end to said box-like structure and free at its other end, means for supporting said closure in erect position, a portion of said closure being foldable to provide a 50 display, and means at the free end of said closure engaging said closure intermediate its ends for holding said display in display position.

13. A carton comprising a box-like structure open at the top and having a guideway along one of the walls thereof, a member connected to said box-like structure and movable along said guideway, a closure for said box-like structure, a hinge for connecting said 55 closure to said member, said member and

closure being jointly movable along said guideway to bring said hinge to a position intermediate the ends of said guideway for restraining said closure from movement about said hinge, said closure being free at one end and foldable to provide a display, and means at the free end of said closure engaging said closure intermediate its ends for holding said display in display position.

70 75 In testimony whereof I have affixed my signature to this specification.
